(57) CLAIM

The ornamental design for a tape dispenser having a transparent casing, as shown and described.

DESCRIPTION

FIG. 1 is a front view of the tape dispenser having a transparent casing showing my new design with a head cover in a retracted position for exposing an application head;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a perspective view thereof in a position during use with the head cover in the retracted position for exposing the application head; and,

FIG. 8 is a front view similar to FIG. 1, with the head cover in an advanced position for covering the application head during non-use.
